UNITED STATES PATENT OFFICE.

BURNHAM C. STICKNEY, OF ELIZABETH, NEW JERSEY, ASSIGNOR TO UNDERWOOD
TYPEWRITER COMPANY, OF NEW YORK, N. Y., A CORPORATION OF DELAWARE.

TYPEWRITING-MACHINE.

1,349,015.

Specification of Letters Patent. Patented Aug. 10, 1920.

Application filed June 15, 1918. Serial No. 240,130.

To all whom it may concern:

Be it known that I, BURNHAM C. STICKNEY, a citizen of the United States, residing in Elizabeth, in the county of Union and 5 State of New Jersey, have invented certain new and useful Improvements in Type-writing-Machines, of which the following is a specification.

This invention relates to mechanism for 10 controlling condensed record sheets in type-writing machines, one of the main features of the invention being the provision of novel means for securing a forward shifting or advance of the record sheet after the completion of the typing of a bill or item, thereby securing a suitable blank space between the records on the bills or the like.

While the devices for advancing the record sheet may be used in various kinds of 20 machines, they are herein shown in connection with a fan-fold machine of the type shown in the Wernery & Smith Patent No. 1,132,055, dated March 16, 1915, in which superposed plies of web are fed around the 25 revoluble platen of an Underwood type-writing machine, sheets of carbon being interleaved with the superposed plies, and the whole forming a unit which loops around the platen, the platen being displaceable upwardly for the purpose of permitting the 30 loop to be straightened or opened out, whereupon the carbons are released and hence may be drawn backwardly to face fresh portions of the webs.

In such machines, after each form is filled up by using the typewriter, it is torn off from the web; but the condensed record sheet remains in the machine, not being torn off, and this enables copies of several forms 40 to be accumulated upon one condensed record, which is usually not a web but in the form of a separate sheet, interposed between the webs and the platen, to form part of the unit.

One of the features of the present improvements consists in the provision of means for advancing the record sheet independently; and this advancing means is preferably connected to the means whereby 50 a release is effected between the platen and the usual feed-rolls that run thereon, for relieving all the work from the control of said rolls. In the present instance, such roll-release is effected by a lifting of the 55 platen, whereby the sheets are liberated, and

therefore to the platen-lifting means I connect a device for advancing the condensed record sheet; although the invention is not limited in all cases to the specific roll-releasing means.

In the specific form of my invention herein illustrated, I provide upon the delivery side of the platen a pair of feed-rolls or devices between which the leading-end of the condensed record sheet is introduced. These 60 rolls, however, are normally separated so that they can do nothing more than guide the condensed record sheet, but when the release is effected between the platen and the bottom feed-rolls, these special feed-rolls are 65 brought into co-action to grip the condensed record sheet, preparatory to advancing the same, and the further rise of the platen away from the bottom feed-rolls is accompanied by the rotation of the special feed-rolls, whereby the condensed record sheet is 70 automatically advanced. This movement is preferably effected by means of a pinion which is fixed upon the shaft of the upper of the two new feed-rolls, which pinion meshes 75 with a stationary segment, which is concentric with the hinge upon which the platen frame swings upwardly at the platen-displacing operation. This upward movement of the platen is therefore accompanied by a 80 positive rotation of one of the special feed-rolls, whereby the condensed record sheet is advanced by co-action with the opposed new feed-roll. This advances the record sheet 85 preferably to the extent of about three line-spaces.

Two line-spaces are sufficient for spacing apart the successive entries or groups upon the condensed record sheet; but an additional advance is preferably made, in order 90 to compensate for the downward drag or retraction of the condensed record sheet, which is apt to occur at the subsequent dropping of the platen back to normal position. The invention may be used either for compensating for this backward creep of the 95 record sheet, or for the purpose of securing the desired blank space between entries upon the record sheet, or for both cases, as in the present form of the invention.

At the initial part of the return movement of the platen from its elevated position, a separation is automatically effected between the special feed-rolls, so that they may not have any tendency to feed the condensed 100 sheet.

record sheet backwardly while the platen is being returned to normal printing position. During such drop of the platen, the upper of the two special feed rolls may revolve idly; while the lower of said rolls, being out of contact does not revolve, but remains in position to be thrown into co-action with the upper roll at the initial part of the succeeding rise of the platen as afore-
10 said.

Thus, the condensed record sheet may be fed forward line by line by the usual line-spacing mechanism, together with the plies of web, whether the same be fan-fold or
15 separate plies, and said condensed record sheet will be automatically spaced between entries or groups thereon, and, in addition, if desired, the backward drag of the condensed record sheet, if it occurs, may be
20 compensated for.

Other features and advantages will hereinafter appear.

In the accompanying drawings,

Figure 1 is a perspective view of a fan-fold machine, showing my invention applied thereto.

Fig. 2 is a sectional side view, showing the parts in their normal position.

Fig. 3 is a view similar to Fig. 2, showing the position of the parts at the initial part of a platen-displacing operation.

Fig. 4 is a view similar to Fig. 3, showing the position of the parts at the end of a platen-displacing operation.

Fig. 5 is a view similar to Fig. 4, showing the position of the parts at the initial part of a platen-returning operation.

Fig. 6 is a fragmentary front elevation of the right-hand side of the machine.

The plies of web 10, which may be either in fan-fold form or separate plies, are led into the machine in the usual manner, and passed forwardly and then downwardly under and around the platen 11 and up in front thereof; the feed-rolls 12, Fig. 2, pressing the work against the platen; said feed-rolls being preferably releasable by means of a finger-piece 13 in the usual manner. In rear of the platen is mounted a carbon carrier 17, Figs. 1 and 2, which is movable backwardly and forwardly upon tracks 18 provided upon the typewriter carriage 19, carbons 20 being connected to blades 21 which are fixed upon said carrier, the blades and carbons alternating with the plies of web, and the rotation of the platen at the line-feeding operations pulling forward not only the web, but also the carbon sheets, together with the carbon carrier.

A condensed record sheet 25 is placed between the webs and the platen in superposed relation with the webs, and is faced by the uppermost carbon of the carbon carrier and drawn forwardly and back with said carbon carrier. The leading end of

said condensed record sheet is introduced between a pair of auxiliary feed-rolls 26, 27, which may be arranged at the delivery side of the platen; these rolls, however, being normally separated, as at Fig. 2, and normally ineffective during the line-feeding operations of the platen, so that the condensed record sheet advances idly between said rolls.

When the platen is lifted with its swing frame 28, Figs. 3 and 4, (comprising arms 29 and a rock shaft or hinge 30, the latter journaled upon the typewriter carriage), to permit the loop of webs and record sheet to be straightened or opened out so that the carbons can be drawn back to face fresh portions of the webs, said rolls 26, 27 are brought together automatically and proceed to rotate, thereby advancing the record sheet 25 independently of the remaining work-sheets or webs 10.

The rolls 26, 27, may be brought together automatically in any desired way, for example, by mounting the under roll 27 upon arms 33 connected by a rock shaft 34, and providing upon said rock shaft a controlling arm 35, which is held in either roll-opening or roll-closing position, by means of a detent 37, which may, for example, be in the form of a V-spring to enter either of two notches 38, 39, provided upon said arm 35. Upon said arm is carried a pin or roller 40, in the path of which is a member in the form of an abutment or cam 41, so that as the platen swing frame 28 rises, said cam 41 intercepts said pin 40 and causes the roll-carrying arm 35 and rock shaft 34 to rotate and the spring 37 to enter the other notch 38 in the arm 35, whereby the under feed-roll 27, Fig. 3, is caused to press the condensed record sheet 25 against the upper feed-roll 26 and hold it there. In the further displacement of the platen frame upwardly, the pin 40, Fig. 3, escapes from the cam 41 while the spring 37 maintains the arm 35 and roll 40 in the new positions.

During this upward displacement of the platen swing frame, a pinion or segment 42 upon a shaft 43 of the upper of the two condensed record feed-rolls 26, by reason of its engagement with a fixed pinion 44 which is concentric with the shaft or hinge 30 of the platen swing frame 28, is caused to rotate, thereby advancing the condensed record sheet 25 in line-feeding direction. The extent of this advance will depend upon the extent of movement of the platen swing frame 28 or the like, and upon the proportions of the pinion 42 and pinion 44; but preferably the advance of the record sheet 25 at this time equals about three or four line-spaces.

To set the auxiliary feed-roll controlling mechanism, so that the lower auxiliary

feed-rolls 27 will be released at the initial part of a platen-returning operation, a second or rear roller 47 on the arm 35 will pass idly over a cam or abutment 48 at the completion of the platen-displacing operation. Said cam 48 is placed in front of the other cam 41 and is pivoted at 49 and supported by a spring 50 to permit said idle movement of the roller 47 thereover until 10 said roller is in a position directly in front of the abutting end of said cam, as in Fig. 4.

In this position of the platen frame, the webs 10 may be adjusted and the carbons 20 retracted while the record sheet 25 is held 15 by the auxiliary feed-rolls 26, 27 against accidental displacement.

During the early portion of the return movement of the platen, the second pin 47 upon said roll-carrying arm 35, Fig. 5, engages the abutment or cam 48 which is in the path thereof, and thereby forces said arm to return to its normal position with the V-spring 37 in the other notch 39 and the lower feed-roll 27 separated from the 25 upper feed-roll 26; said pin 47 then escaping passes said abutment 48, not meeting with further interference during the remainder of the return movement of the platen down to normal position. Hence, 30 the principal portion of the rotation of the roll pinion 42 during the return movement of the platen is idle, since the rolls 26, 27 are separated, and the condensed record sheet 25 is therefore not drawn back by said 35 rolls. If said record sheet is retracted slightly by reason of the depression of the platen, this will be a matter of no moment, since the original advance of said record sheet effected as aforesaid by its rolls, will 40 be much greater than the incidental retraction or dragging back of the record sheet during the downward return of the platen aforesaid.

To set the auxiliary feed-roll controlling mechanism into position for a succeeding platen-displacing operation, the first pin or roller 40, which has previously co-acted with the cam 41 for moving the feed-rolls 26, 27 into effective position, rides back idly 45 over said cam 41 until the roller 40 is moved in front of the abutting end of said cam 41, in which position said cam will be effective to swing the arm 35 when the platen is lifted. To permit said first pin 50 or roller to thus move over the cam 41, said cam is also provided with a pivot 49 and supported by a spring 50 in a manner similar to the forward cam 48.

From the foregoing, it will be understood 60 that the record sheet 25 will be line-fed together with the plies of web 10 and that it will also receive an extra advance movement independently of said plies, so that it is not necessary for the operator to bear in

mind to operate the line-space handle 51, 65 Fig. 1, after the completion of the typing of any form upon the web 10, but that the necessary spacing apart of the entries upon the record sheet will be made automatically.

While other methods may be adopted for 70 releasing the record sheet from the rolls 26, 27, still it is preferred to release it after the rearrangement of the webs, as explained, and preferably at the beginning of the return-stroke of the platen. 75

Variations may be resorted to within the scope of the invention, and portions of the improvements may be used without others.

Having thus described my invention, I claim:

1. In a typewriting machine, the combination of a platen; a line-space wheel therefor; means to coöperate with said line-space wheel for feeding around the platen webs, carbon sheets and a record sheet as a unit in superposed relation, with the record sheet between the webs and the platen; means for displacing the platen to ease the carbon sheets and permit them to be shifted along the webs; and means connected to 90 the platen-displacing means for advancing said record sheet relatively to said webs and platen. 85

2. In a typewriting machine, the combination of a platen; means for feeding webs 95 and a record sheet as a unit in superposed relation line by line around said platen in the form of a loop; means for opening out the loop; and means for automatically feeding said record sheet during the operation 100 of said loop-opening means.

3. In a typewriting machine, the combination of a platen; means for feeding webs, a record sheet and interleaved carbons around the platen; means operable for retracting said carbons; means operable for straightening said webs and carbons to permit the retraction of said carbons; and means for advancing said record sheet during the straightening operation. 105 110

4. In a typewriting machine, the combination of a platen, feed-rolls coöoperating with said platen for feeding webs and a record sheet as a unit around said platen, with the record sheet between the webs and the platen, means to displace the platen and thereby effect separation between the feed-rolls and platen, and means other than said feed-rolls and operatively associated with said separating means, for feeding 120 said record sheet relatively to the webs. 115

5. In a typewriting machine, the combination of a platen, releasable feed-rolls coöperating with said platen for feeding webs and a record sheet as a unit around said 125 platen, with the record sheet between the webs and the platen, means for displacing the platen, auxiliary feed-rolls for feeding

said record sheet relatively to the platen, and means for automatically operating said auxiliary feed-rolls concomitantly with the platen-displacing operation.

- 5 6. In a typewriting machine, the combination of a platen, releasable feed-rolls below said platen and coöperating therewith for feeding webs and a record sheet as a unit around the platen, with the record sheet between the webs and the platen, means for displacing the platen, auxiliary feed-rolls above said platen, and means automatically coöperating with said auxiliary feed-rolls for feeding said record sheet relatively to the platen when the platen is displaced.

- 10 7. In a typewriting machine, the combination with a platen for line-feeding a web and a record sheet, of means for straightening the web, and means for advancing said record sheet around the platen during a web straightening operation, said advancing means effective to hold said record sheet against displacement during re-
15 adjustment of the web.

- 20 8. In a typewriting machine, the combination with a platen for line-feeding webs, a record sheet and interleaved carbons; of means for retracting said carbons; means for displacing the platen to enable the retraction of the carbons and the re-adjustment of the webs; and feed rolls for advancing said record sheet during the platen displacing operation.

- 25 9. In a typewriting machine, the combination with a platen for line-feeding webs, a record sheet and interleaved carbons; of means for retracting said carbons; means for displacing the platen to enable the re-
30 traction of the carbons and the re-adjustment of the webs; and feed rolls for advancing said record sheet during the platen displacing operation, said feed rolls acting to hold the record sheet against displacement during carbon-retracting and web-adjusting operations.

- 35 10. In a typewriting machine, the combination with a platen for carrying webs, a record sheet and interleaved carbons; means for advancing said webs, carbons and record sheet simultaneously; feed rolls for advancing said record sheet independently; means for retracting said carbons; means for displacing said platen to enable the re-
40 traction of said carbons, means for causing said feed rolls to rotate effectively when said platen is displaced, and means causing said feed rolls to rotate ineffectively when said platen is returned.

- 45 11. In a typewriting machine, the combination of a platen, means for simultaneously feeding a plurality of superposed sheets as a unit in the form of a loop around said platen, means for feeding a single one of

said sheets independently of the others, 65 mechanism operable to permit the opening out of the loop, and means for automatically actuating said single sheet-feeding means at the operation of said mechanism.

70 12. In a typewriting machine, the combination of a platen, means for simultaneously feeding a plurality of superposed sheets as a unit line by line around said platen, platen-moving mechanism, means for feeding a single one of said superposed sheets relatively to the others while the latter remain in place in the machine, and means for automatically actuating said single sheet-feeding means at the operation of the platen-moving mechanism.

75 13. In a typewriting machine, the combination of a platen; means for feeding webs, a record sheet and interleaved carbons around said platen; means operable for retracting said carbons; means operable for straightening said webs and carbons to permit the retraction of said carbons, said means causing a retraction of said record sheet when returned to normal position; and means for compensating for the retraction 80 of said record sheet.

85 14. In a typewriting machine, the combination of a platen; means for feeding webs, a record sheet and interleaved carbons around said platen; means operable for re-
90 tracting said carbons; means operable for straightening said webs and carbons to permit the retraction of said carbons, said means causing a retraction of said record sheet when returned to normal position; and 100 means for compensating for the retraction of said record sheet during a straightening operation.

95 15. In a typewriting machine, the combination of a platen; means for feeding webs, a record sheet and interleaved carbons around said platen; means operable for re-
105 tracting said carbons; means operable for straightening said webs and carbons to permit the retraction of said carbons, said means causing a retraction of said record sheet when returned to normal position; and means for compensating for the retraction 110 of said record sheet prior to said retraction of the record sheet.

115 16. In a typewriting machine, the combination of a platen; means for feeding webs, a record sheet and interleaved carbons around said platen; means operable for re-
120 tracting said carbons; means operable for straightening said webs and carbons to permit retraction of said carbons, said means causing a retraction of said record sheet when returned to normal position; and means for advancing said record sheet an 125 amount equivalent to or greater than the amount of said record sheet retraction.

17. In a typewriting machine, the combi-

- nation of a platen; rolls for feeding webs, a record sheet and interleaved carbons around said platen; a carbon carriage for retracting said carbons; a platen frame displaceable for straightening the webs, record sheet and carbons to permit the retraction of said carbons by said carriage, said platen causing a retraction of said record sheet when returned to normal position; and auxiliary feed rolls for advancing said record sheet an amount equal to or greater than the amount of said record sheet retraction. 5 70
18. In a typewriting machine, the combination of a platen; mechanism for feeding webs, a record sheet and interleaved carbons around said platen; a carbon carriage for retracting said carbons; a platen frame displaceable for straightening said webs, record sheet and carbons to permit the retraction of said carbons by said carriage; and feed rolls for advancing said record sheet during the displacing of said platen frame, said feed rolls being ineffective during the return of said platen. 10 75
19. In a typewriting machine, the combination of a bodily displaceable platen, releasable feed rolls coöperating with said platen for feeding webs and a record sheet around said platen, and feed rolls independent of said platen and controlled by the bodily movement of said platen for feeding said record sheet when the other feed rolls are released. 20 80
20. In a typewriting machine, the combination of a swingable platen, feed rolls coöperating with said platen for feeding a work-sheet around said platen, and auxiliary feed rolls for said work-sheet rotatable in two directions by the swinging of said platen, effective when rotated in one direction, and ineffective when rotated in the other direction. 25 85
21. In a typewriting machine, the combination with a platen, of a swingable frame for said platen, means coöperating with said platen for feeding a work-sheet around said platen, and means coöperating with said frame for feeding said work-sheet, the effectiveness of both said feeding means being controlled by the movement of said frame. 30 90
22. In a typewriting machine, the combination with a revolvable platen, feed-rolls coöperating with said platen for feeding a plurality of work-sheets, feed-rolls independent of the platen for feeding one of said work-sheets when the other feed-rolls are ineffective, and means controlled by a bodily movement of the platen for determining the effectiveness of said feed-rolls. 35 95
23. In a typewriting machine, the combination of a platen, primary feed-rolls for simultaneously advancing webs and a record sheet around said platen, auxiliary feed-rolls for advancing said record sheet, means for automatically rendering said auxiliary feed-rolls effective when said primary feed-rolls are released, and means for automatically releasing said auxiliary feed-rolls after said record sheet is advanced. 40 100
24. In a typewriting machine, the combination with a platen, of a displaceable platen frame, means for feeding webs and a record sheet around said platen effective when said platen is in normal position, mechanism normally ineffective for feeding said record sheet, and means for rendering said record-sheet-feeding mechanism effective when said frame is released. 45 105
25. In a typewriting machine, the combination with a platen, of a displaceable platen frame, primary feed-rolls for feeding webs and a record sheet to and around said platen when said platen is in normal position, auxiliary feed-rolls normally ineffective for feeding said record sheet, and means for rendering said auxiliary feed rolls effective when said platen frame is displaced. 50 110
26. In a typewriting machine, the combination with a platen; of a platen frame displaceable to permit the retraction of carbons; primary feed-rolls for feeding webs, record sheet and carbons to and around said platen; auxiliary feed-rolls normally ineffective for feeding said record sheet; means for rendering said auxiliary feed rolls effective at the initial part of a platen-displacing operation; and means rendering said auxiliary feed-rolls ineffective at the initial part of a platen-returning operation. 55 115
27. In a typewriting machine, the combination with a platen; of a platen frame displaceable to permit the retraction of carbons; primary feed-rolls for feeding webs, record sheet and carbons to and around said platen when said platen is in normal position; auxiliary feed-rolls for feeding said record sheet; means for automatically causing said auxiliary feed-rolls to grip said record sheet at the initial part of a platen-displacing operation; and means for automatically causing said auxiliary feed-rolls to release said record sheet at the initial part of a platen-returning operation. 60 120
28. In a typewriting machine, the combination with a platen; of a platen frame displaceable to permit the retraction of carbons; primary feed-rolls for feeding webs, record sheet, and carbons to and around said platen; substantially stationary auxiliary feed-rolls for feeding said record sheet; movable auxiliary feed-rolls normally ineffective; and means for moving said movable auxiliary feed-rolls into engagement with said record sheet and said stationary auxiliary feed-rolls at the initial part of a platen-displacing operation. 65 125
29. In a typewriting machine, the combination with a platen; of a platen frame 130

- displaceable to permit the retraction of carbons; primary feed-rolls for feeding webs, record sheet and carbons to and around said platen; substantially stationary auxiliary feed-rolls for feeding said record sheet; movable auxiliary feed-rolls normally ineffective; means for moving said movable auxiliary feed-rolls into engagement with said record sheet and said stationary auxiliary feed-rolls at the initial part of a platen-returning operation.
30. In a typewriting machine, the combination with a platen; of webs, a record sheet and interleaved carbons around said platen; a platen frame displaceable to permit the retraction of said carbons; a paper table on said frame; primary feed-rolls for feeding said webs and carbons over said table; auxiliary feed-rolls over said table; and feed-rolls under said table coöperating with said feed-rolls over said table for feeding said record sheet.
31. In a typewriting machine, the combination with a platen, of mechanism for line-spacing around said platen both a web and a record sheet between said web and platen, means shiftable for permitting independent adjustment of said web to bring a succeeding section thereof to the writing point, and means connected to said shiftable means, for automatically line-spacing said record sheet.
32. In a typewriting machine, the combination with a platen; of a platen frame displaceable to permit the retraction of carbons; means for feeding webs, record sheet and carbons to and around said platen; substantially stationary auxiliary feed-rolls to run upon one side of said record sheet; movable auxiliary feed-rolls normally ineffective and mounted to run upon the other side of said record sheet; a rock shaft on the platen frame for carrying said movable auxiliary feed-rolls; an arm on said rock shaft; and a substantially stationary member coöoperating with said arm for swinging said rock shaft to move said movable feed-rolls into effective coöperation with said stationary rolls at the initial part of a platen-displacing operation.
33. In a typewriting machine, the combination with a platen; of a platen frame displaceable to permit the retraction of carbons; means for feeding webs, record sheet and carbons around said platen; substantially stationary auxiliary feed-rolls to run upon one side of said record sheet; movable auxiliary feed-rolls normally ineffective and mounted to run upon the other side of said record sheet; a rock-shaft on the platen frame for carrying said movable auxiliary feed-rolls; an arm on said rock shaft; and a substantially stationary member coöoperating with said arm for swinging said rock shaft to move said movable feed-rolls into effective coöperation with said stationary rolls at the initial part of a platen-displacing operation.
34. In a typewriting machine, the combination of a platen; feed-rolls for feeding webs, a record sheet and interleaved carbons around said platen; a carbon carriage for retracting said carbons; a platen frame displaceable for straightening the webs, record sheet and carbons to permit the retraction of said carbons by said carriage, said platen causing a retraction of said record sheet when returned to normal position; auxiliary feed-rolls for advancing said record sheet an amount equal to or greater than the amount of said record-sheet retraction; and means for positively and automatically driving said auxiliary feed-rolls when the platen frame is displaced.
35. In a typewriting machine, the combination of a platen; rolls for feeding webs, a record sheet and interleaved carbons around said platen; a carbon carriage for retracting said carbons; a platen frame displaceable for straightening the webs, record sheet and carbons to permit the retraction of said carbons by said carriage, said platen causing a retraction of said record sheet when returned to normal position; auxiliary feed-rolls for advancing said record sheet an amount equal to or greater than the amount of said record sheet retraction; and gearing controlled by said platen frame for positively and automatically driving said auxiliary feed-rolls when the platen frame is displaced.
36. In a typewriting machine, the combination of a platen; rolls for feeding webs, a record sheet and interleaved carbons around said platen; a carbon carriage for retracting said carbons; a platen frame displaceable for straightening the webs, record sheet and carbons to permit the retraction of said carbons by said carriage, said platen causing a retraction of said record sheet when returned to normal position; auxiliary feed-rolls for advancing said record sheet an amount equal to or greater than the amount of said record sheet retraction; a shaft on said frame on which said feed-rolls are fast; an arcuate gear on said shaft; and a stationary arcuate gear meshing with the gear on said shaft for positively driving said auxiliary feed-rolls.
37. In a typewriting machine, the combination of a platen; rolls for feeding webs, a record sheet and interleaved carbons around said platen; a carbon carriage for retracting said carbons; a platen frame swingable for straightening the webs, record sheet and carbons to permit the retraction of said carbons by said carriage, said platen causing a retraction of said record sheet when returned to normal position; auxiliary feed-rolls for advancing said record sheet an amount equal to or greater than the amount of said record sheet retraction; a shaft on said frame on which said feed-rolls are fast; an arcuate gear on said shaft; and a stationary arcuate gear meshing with the gear on said shaft for positively driving said auxiliary feed-rolls.

tion of said carbons by said carriage, said platen causing a retraction of said record sheet when returned to normal position; a hinge on which said platen frame swings; 5 auxiliary feed-rolls for advancing said record sheet an amount equal to or greater than the amount of said record sheet retraction; a shaft on said platen frame on which said auxiliary feed-rolls are fast; an arcuate gear on said shaft; and a stationary 10 arcuate gear on said hinge meshing with the gear on said shaft for positively and effectively driving said auxiliary feed-rolls when said platen is swung to carbon-retracting 15 position.

38. In a typewriting machine, the combination with a platen, of means for feeding webs, carbons and an underlying record sheet around said platen, means for displacing the platen to enable the retraction of 20 said carbons, feed-rolls for advancing said record sheet during the platen-displacing operation, means for causing the feed-rolls to grip said record sheet in a platen-displacing operation, means for causing the 25

feed-rolls to release said record sheet in a platen-returning operation, and means for holding said feed-rolls in gripping or in releasing position.

39. In a typewriting machine, the combination of a platen, a line-space wheel therefor, means to coöperate with said line-space wheel for feeding around the platen webs, carbon sheets and a record sheet as a unit in superposed relation, with the 30 record sheet between the webs and the platen, means for displacing the platen to ease the carbon sheets and permit them to be shifted along the webs, and means connected to the platen-displacing means for 35 advancing said record sheet relatively to said webs and platen, said record-sheet-advancing means including an actuator which is ineffective during the feeding of said unit.

BURNHAM C. STICKNEY.
